COOKER

Robert W. Thomas, Wichita, Kans., assignor to William D. Devore and R. A. Devore, Wichita, Kans.

Continuation-in-part of design application Ser. No. 196,254, Nov. 5, 1971, now Patent No. 229,625, dated Dec. 18, 1973. This application Feb. 12, 1973, Ser. No. 331,551

Term of patent 14 years

Int. Cl. D7—02

U.S. Cl. D7—94

FIG. 1 is a top plan view of a cooker showing my new design;

FIG. 2 is a top perspective view;

FIG. 3 is an elevational view from the side opposite that seen in FIG. 2; and

FIG. 4 is a bottom plan view.

This application is a continuation-in-part of design application Ser. No. 196,254, filed Nov. 5, 1971, and now patent No. D. 229,625, dated Dec. 18, 1973.

I claim:

The ornamental design for a cooker, substantially as shown and described.
